US00D887457S

(12) **United States Design Patent** (10) Patent No.: **US D887,457 S**
Adachi et al. (45) Date of Patent: **** Jun. 16, 2020**

(54) **CONSOLE FOR CONSTRUCTION MACHINE**

(71) Applicant: **KOBELCO CONSTRUCTION MACHINERY CO., LTD.**, Hiroshima-shi, Hiroshima (JP)

(72) Inventors: **Kaoru Adachi**, Hiroshima (JP); **Masanori Sakatani**, Hiroshima (JP); **Shintaro Sakitani**, Hiroshima (JP); **Keiji Yamamoto**, Hiroshima (JP)

(73) Assignee: **KOBELCO CONSTRUCTION MACHINERY CO., LTD.**, Hiroshima-Shi (JP)

(**) Term: **15 Years**

(21) Appl. No.: **29/674,927**

(22) Filed: **Dec. 27, 2018**

(30) **Foreign Application Priority Data**

Jul. 10, 2018 (JP) 2018-015169

(51) LOC (12) Cl. **15-03**

(52) U.S. Cl.

USPC **D15/28**; D15/17

(57) **CLAIM**

The ornamental design for a console for construction machine, as shown and described.

DESCRIPTION

FIG. 1 is a first perspective view of a console for construction machine;

FIG. 2 is a second perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The broken lines depict portions of the console for construction machine in which the design is embodied that are not considered part of the claimed design.

The dashed lines show a boundary between the claimed design and unclaimed portions.

1 Claim, 7 Drawing Sheets
